UNITED STATES PATENT OFFICE.

RALPH G. DETMER, OF HAMILTON, OHIO, ASSIGNOR TO THE AMERICAN FROG & SWITCH COMPANY, OF HAMILTON, OHIO, A CORPORATION OF OHIO.

RAILWAY FROG.

Application filed April 25, 1927. Serial No. 186,302.

My invention relates to railway frogs, especially to that character of railway frog employing a movable wheel supporting section arranged to be moved for continuity in riding surface of a track.

It is the object of my invention to provide new and improved means whereby continuity in riding surface of a track is obtained; further, to provide novel railway track construction embodying converging rails provided with spread portions for receiving a frog block and avoiding shifting relation between the frog block and such converging portions of said rails; further, to provide novel railway frog construction wherein continuity of riding surface of a track is assured, and whereby ready passage over a diagonally arranged track is assured.

The invention will be further readily understood from the following description and claims, and from the drawings, in which:

Fig. 1 is a plan view of a railway track construction embodying my invention and partly broken away.

Fig. 2 is a side elevation of the same.

Fig. 3 is a cross-section of the same, taken on the line 3—3 of Fig. 1, and partly broken away.

Fig. 4 is a similar cross-section, taken on the line 4—4 of Fig. 1.

Fig. 5 is a similar cross-section, taken on the line 5—5 of Fig. 1.

Fig. 6 is a perspective view of the block; and,

Fig. 7 is a bottom perspective view of the shiftable riding section.

I have exemplified my invention as applied to a railway track construction embodying a main track employing rails 11, 12 and 13, and a diagonal crossing track, which may be termed a side-track, embodying rails 14 and 15 and a supplemental track not shown. A block 17 has thereon a fixed frog point 18, at the sides of which there are flangeways 19, 20, merging into a throat 21 and a mouth 22 in advance of the frog point. The block has a heel extension 23, forming recesses 24, 25, at the sides of the rear end of the block.

The block is provided with riding sur-

faces 31, 32, at one side of the frog point, which are spaced apart lengthwise of the flangeways by a space 33. A shiftable riding section 35 is located in said space, and is shown pivoted to the block on a pivot lug 36, received in a pivot hole 37 in said block, and held to said block by a securing pin 38. This space has a bottom wall 39 and merges into the flangeways in the block. The bottom wall forms a supporting surface for the shiftable riding section on which the swinging end of the shiftable riding section is moved laterally toward and from the frog point.

The movement of the shiftable riding section is obtained in suitable manner, and may be automatic for normally moving the shiftable riding section into coactive relation with the frog point and locating the shiftable riding section in the flangeway at the side of the frog point for continuity of riding surface along the main track. If desired, the shiftable riding section may have connection with a manual lever or with a tower controlling lever for locating the shiftable riding section in desired position.

The rails 11 and 14 are shown converging toward the frog point. They are provided with spread portions, shown generally at 41, 42, between which the block is received and secured. These spread portions may include outwardly diverging portions 43, 44, preferably bent integrally from the converging main portions of the rails, which spreading portions merge into converging portions 45, 46, which in turn merge into diverging portions 47, 48, respectively substantially parallel with the rails 15 and 12. The block is exemplified as comprising side walls 51, forming tongues, received in the inner side channels in the bulging portions of the rails 11, 14, the lower ends of these side walls being supported by the bases of said rails.

A separating block 53 is received between the converging end portions of the rails 11, 14, being received in the inner side channels of said rails.

The heel extension of the block is provided with tongues 54, respectively received

in the side channels of the rails 12, 15. Blocks 55 are received between the ends of said rails and the lapping ends of the reinforce rails or bars for the frog block, these separating blocks being provided with tongues received in the side channels of said rails.

Bolts 56 are received through said frog block and said reinforcing rails or bars for 10 rigidly securing the same together, similar bolts being received through the rails 11 and 14 and the separating block 53, and through the lapping portions of the reinforce rails or bars and the rails 12, 15, the separating 15 blocks 55, and the heel extension 23 of the frog block 17. Suitable nuts 57 and lock washers 58 are received over the bolts for clamping the parts rigidly together.

In the present exemplification, the bulged 20 portions 41, 42, which form the reinforce rails, are integral with the rails 11, 14, and encompass the frog block, and the rear ends of said reinforce rails overlap the rails 12, 15, in rear of the frog block, and the heel extension 25 of the frog block, said lapping portions of said rails and said heel extension being secured together, whereby creeping of the frog block and of said rails is definitely prevented.

30 The frog block is preferably provided with a web 61 which extends between the side walls of the frog block. The riding surfaces of the frog block are preferably located on said web.

35 The rear end of the heel extension may be provided with an easer surface 62, which is arranged to be contacted by the so-called false flange at the outer end of the tread of the wheel, so as to ease the wheel on to the 40 rails and the riding surfaces of the frog. In practice the wheel 64 usually becomes worn adjacent to its flange 65, the riding periphery of the wheel adjacent to its flange having an annular groove 66 formed therein by pressure and wear, and leaving the outer end 67 of the tread of the wheel of greater diameter than the diameter of said wheel at said groove, and forming the so-called false flange. This is exemplified in dotted lines 50 in Fig. 4.

The heel ends of the bulge of the reinforce rails are also preferably provided with easer faces 69, which slant downwardly and forwardly for forming mouths at the heel end 55 of the frog block, to insure ready entrance of the flanges of the traveling wheels into the flangeways in the frog block.

An easer rail 71 having an easer face 72 may be located at the outer face of the rail 60 11, so as to ease the false flanges on the wheels traveling over the main track upon the diverging portion of said rail and the riding surfaces on the frog block, and to ease the wheels off said rail and riding surfaces. 65 This easer rail may be secured to the rails

and blocks at the side thereof by the fastening means securing said rails and blocks together, suitable filler blocks being located in the proximate side channels of said rails 11 and 71. This additional easer rail, however, 70 is not essential, because the diverging portions 43, 44, of the rails 11, 14, are presented slantingly toward the false flanges of the wheels passing thereover, so as to ease the wheels with relation to the frog block and 75 the rails, which easing is emphasized by the rounded edges of the heads of said diverging portions of said rails.

The shiftable riding section 35 may be normally urged toward the frog point, as by 80 means of springs 75 between the reinforce rail at the side of the frog block and a lug 76 extending downwardly from the shiftable riding section through a slot 77 in the upper wall of the frog block. A bolt 78 is received through the reinforce rails, through a hole 79 in a depending lug 80 of the frog block and a hole 81 in the depending lug 76, the spring being received between the last-named lug and a flange bushing 82 in a hole in the reinforce rail 41, a nut 83 being received over a reduced threaded end of said bolt and suitably secured in place for maintaining the parts in connected relation. 85

If desired, the shiftable riding section may be manually operated, as by means of a rod 85 received through a lug 86 extending from the lug 76. The head 87 of the rod limits inward movement of the shiftable riding section. The rod 85 may have articulation 88 with a suitable bell crank lever 89, pivoted on a fixed pivot 90 to the road bed, and operated by a rod 91 articulated with said bell crank lever at 92. The rod 91 may be operated in suitable manner, as by means of an ordinary weighted manually operated lever at the side of the track, or the rod 91 may lead to a suitable tower control for operating the shiftable riding section. 100

The reinforce rail 41 may be provided with a recess 95, the bottom of which forms a support for the shiftable riding section. The shiftable riding section is formed with an upper wall 96, which forms a cover for the space 97 between the inner flange 98 of the 110 shiftable riding section and the reinforce rail portion 41, this cover being also received over the spring and its connections for protecting the same and said space from dirt, snow and injury. 115

The end 101 of the shiftable riding section and the end walls 102 of the recesses 33 and 97 may be formed on an arc described from the pivotal axis of the pivoted riding section as a center, for preventing wedging action 125 between said faces and insuring freedom of movement of the riding section.

A tread guard 105 may be provided at the side of the rail frog opposite to the shiftable riding section. It is shown as part of 130

the block 17 and is arranged to be engaged by the outer end of the tread of the wheel passing over the rails, for shifting the flange of the rail inwardly so that when the wheel 5 passes the frog point, the flange of the wheel will be spaced inwardly from said frog point for preventing contact with the frog point and thereby preventing injury to the frog point. This construction also insures positive 10 movement of the shiftable riding section, which is moved by the flange end of the wheel. This tread guard may be provided with easer faces 106 at the respective ends thereof.

15 The shiftable riding section is at its swinging end provided with a receding inner wall 107 arranged to be engaged by the flange traveling in the flangeway 20 toward the front of the frog along the siding, for shifting the shiftable riding section laterally away from the frog, so that said flange may readily pass through the throat and the mouth of the frog. When the railway vehicle is moving in the opposite direction 20 along the siding, the flange of the wheel strikes the wall 108 of the shiftable riding section which normally fills the gap between the riding surfaces at the frog in the main track, for readily shifting said shiftable riding section to permit passage of the vehicle along the siding track. The springs 75 normally retract the shiftable riding section toward the frog point.

25 The frog block is preferably of wear resisting metal, for instance a manganese steel casting.

The connection between the lug 86 and the rod 85 is preferably a loose connection so that when the shiftable riding section is 30 adjacent to the frog point it may readily be moved by the wheel against the resistance of the spring, in which relation the lug 86 moves along the rod 85. This places the automatic yielding of the shiftable riding 35 section independent of the manual control thereof.

Having thus fully described my invention, what I claim as new and desire to secure by Letters Patent, is:

40 1. A railway frog comprising a block having thereon a frog point, riding surfaces at substantial track riding level at the respective sides of said frog point, and a tread guard at the side of said riding surfaces arranged for coaction therewith by the tread 45 end of a wheel, and a shiftable riding section mounted on said block between selective ones of said riding surfaces and comprising a portion arranged for movement toward and from said frog point.

45 2. A railway frog comprising a block having thereon a frog point and riding surfaces at substantial track riding level, a shiftable riding section mounted on said block between selective ones of said riding surfaces

and comprising a portion arranged for movement toward and from said frog point, and a tread guard at the side of said riding surfaces arranged for coaction therewith by the tread end of a wheel for moving the 50 flange of said wheel axially beyond said frog point and into coactive relation with said shiftable riding section.

3. In a railway frog, the combination of a frog point, a flangeway at one side thereof, of, riding portions at the side of said flangeway, said riding portions having a space between them extending lengthwise of said flangeway, a movable riding section in said space comprising a portion movable laterally toward and from said frog point and arranged to be received in said flangeway, and a tread guard at the other side of said frog point arranged for coaction therewith by the tread end of a wheel for moving the 55 flange of said wheel axially beyond said frog point and into coactive relation with said movable riding section.

4. In a railway frog, the combination of a frog point, a flangeway at the side thereof, 60 riding portions at the side of said flangeway, said riding portions having a space between them extending lengthwise of said flangeway, a reinforce rail at the outside of said riding portions, and a movable riding section in said space comprising a portion movable laterally toward and from said frog point and arranged to be received in said flangeway, and said reinforce rail provided with a supporting surface for said movable 65 riding section.

5. In a railway frog, the combination of a frog block provided with a frog point and riding surfaces having an interruption therein, a reinforce bar at the side of said frog 70 block, a shiftable riding section located in said interruption and pivoted to said frog block, and a spring between said reinforce bar and said shiftable riding section, said shiftable riding section comprising a flange 75 normally spaced from said reinforce bar and a cover received over said space and said spring and supported by said reinforce bar.

6. In a railway frog, the combination of a frog point, riding portions having riding 80 surfaces at substantial track level at the respective sides of said frog point, a shiftable section at the side of said frog point, said shiftable section provided with a riding surface complementary to said first-named riding 85 surface, supporting means for said shiftable section, reinforce bars at the outside of said riding portions and means rigidly connecting said frog point, said riding portions and said reinforce bars, and said reinforce bars 90 provided with a supporting face for said shiftable section.

7. In a railway frog, the combination of a block having thereon a frog point, flangeways at the respective sides of said frog 95

point, said flangeways merging in advance of said frog point, and riding surfaces substantially at track riding level at the respective sides of said flangeways, a shiftable riding section having thereon a riding surface complementary to said first-named riding surfaces, said riding section mounted on said block, said block having a heel extension in rear of said frog point, and track rails at 10 the respective sides of said heel extension, said frog point and said heel extension having riding surfaces thereon complementary to said first-named riding surfaces, and the rear end of said heel extension provided with an 15 inclined riser surface between said track rails.

8. In a railway frog, the combination of a block having thereon a frog point, flangeways at the respective sides of said frog point, said flangeways merging in advance 20 of said frog point, riding surfaces substantially at track riding level at the respective sides of said flangeways, and a tread guard extending above said riding surfaces at the 25 side of said riding surfaces and arranged for having the tread end of a wheel coact therewith for shifting the flange of the wheel laterally beyond said frog point, a shiftable riding section having thereon a riding surface 30 complementary to said first-named riding surfaces, said riding section mounted on said block, said block having a heel extension in rear of said frog point, and track rails at the respective sides of said heel extension, 35 said frog point and said heel extension having riding surfaces thereon complementary to said first-named riding surfaces, and the rear end of said heel extension provided with an inclined riser surface between 40 said track rails.

9. In a railway frog, the combination of a block having thereon a frog point, flangeways at the respective sides of said frog point, said flangeways merging in advance 45 of said frog point, and riding surfaces substantially at track riding level at the respective sides of said flangeways, a shiftable riding section having thereon a riding surface complementary to said first-named riding surfaces, said riding section mounted on said block, said block having a heel extension in rear of said frog point, rails at the respective sides of said heel extension, 50 said frog point and said rear extension having riding surfaces at substantial track level, the heel of said rear end extension having an inclined riser surface between said track rails, and reinforce bars at the respective sides of said block, said reinforce 55 bars provided with easer faces at the outer walls of said flangeways for coaction therewith by the wheel flanges riding in said flangeways.

10. In railway track construction, the 60 combination of a block comprising a frog

point, flangeways at the respective sides of said frog point, and riding surfaces at the respective sides of said flangeways, said riding surfaces provided with an interruption at the side of said frog point, a movable 70 riding section in said interruption, said movable riding section pivoted to said block, converging rails in advance of said block, said rails provided with spread portions at the sides of said block, said block received 75 between said spread portions, and means rigidly securing said spread portions and said block together.

11. In railway track construction, the combination of a block comprising a frog 80 point, flangeways at the respective sides of said frog point, and riding surfaces at the respective sides of said flangeways, converging rails in advance of said block, said rails provided with spread portions at the 85 sides of said block, said block received between said spread portions, means rigidly securing said spread portions and said block together, said riding surfaces and said spread portions provided with mating surface interruptions, and a movable riding section in said interruptions.

12. In railway track construction, the combination of converging rails provided 90 with spread portions, a block secured between said spread portions, and a shiftable riding section pivoted to said block, said block provided with a frog point, a flangeway at the side of said frog point and a recess having a bottom wall forming a support for said shiftable riding section, and said spread portion at the side of said recess provided 95 with a supporting surface for said shiftable riding section.

13. In railway track construction, the combination of converging rails provided 100 with spread portions, a block secured between said spread portions, a shiftable riding section pivoted to said block, said block provided with a frog point, a flangeway at 105 the side of said frog point and a recess having a bottom wall forming a support for said shiftable riding section, and said spread portion at the side of said recess provided 110 with a supporting surface for said shiftable riding section, and resilient means normally urging said shiftable riding section toward 115 said frog point.

14. In railway track construction, the combination of a frog block provided with 120 a frog point and riding surfaces provided with an interruption, a shiftable riding section in said interruption, said shiftable riding section pivoted to said frog block, converging rails provided with bulging portions in which said frog block is received, and means rigidly securing said bulging 125 portions and said frog block together.

15. In railway track construction, the combination of a frog block provided with 130

a frog point, riding surfaces provided with an interruption and a heel extension, a shiftable riding section in said interruption, converging rails at the respective sides of said heel extension, converging rails in advance of said frog block and having outwardly bulged portions integral therewith encom-

passing said frog block and having rear ends overlapping said first-named rails at the sides of said heel extension, and means 10 securing said rails and said block together.

In testimony whereof, I have hereunto signed my name.

RALPH G. DETMER.
